Claims priority, application Sweden, Apr. 17, 1956

4 Claims. (Cl. 22—113.5)

This invention relates to centrifugal casting of tubular, metallic bodies in hot, permanent molds, the inner surface of which as a rule is furnished with a thin lining of fireproof and heat-insulating material with the object of inter alia, protecting the inner surface of the mold from damage by the molten metal. The casting of the metal is most frequently effected in the simplest manner, that is through a runner pot which is inserted in one end of the mold. Under the effect of the centrifugal forces the metal is then spread along the entire inner surface of the mold.

Even if the mold is furnished with the above mentioned lining it has nevertheless proved difficult to entirely protect the inner surface of the mold at the spot where the molten metal strikes the mold during casting. The mold gradually develops a network of cracks or fissures into which the metal penetrates at every casting. Corresponding irregular protuberances are formed on the outside of the case body and cause long scratches in the mold when the body is extracted. During the next casting operation these scratches in the mold naturally cause corresponding ribs on the cast body and thus give it an unsatisfactory surface.

Finally, the mold must be discarded or reboored to a larger diameter. The damage to the mold would of course be still greater if it were not lined with the above mentioned coating.

To avoid these disadvantages it has been suggested that an exchangeable collar or sleeve of suitable material be attached coaxially to the casting end of the mold and, either inserted into or affixed to the end of the mold so that the molten metal first strikes this part of the mold and not the mold proper. The fact that the sleeve gradually develops a damaged surface does not, of course, affect the surface of the mold proper or the surface of the cast body. The sleeve can easily be replaced by a new one when required.

In practice, however, the sleeves give rise to serious difficulties however well they may be fitted. It is very difficult if not impossible in practice to affix the sleeve inside the mold, or at its end, without a certain space occurring between the wall of the mold and the sleeve. Even if the space or gap is very small, the molten metal will force its way into it under the influence of the very high centrifugal forces and form thin fins at the end of the cast body. If the metal has once forced its way into the gaps they will become larger and larger in subsequent castings, and consequently larger fins will be formed on the castings. When these castings are extracted the fins score the inner surface of the mold, and if the fins become very large they may cause the tubular body to shrink off in two halves after the casting, as it is sometimes locked at the casting end and cannot shrink freely. In casting a metal such as cast iron which owing to the rapid cooling in the said gaps solidifies to hard, white iron, the scratches in the mold will be still more serious.

If the sleeve is placed inside the mold, other difficulties are also encountered. Even if it is fitted as carefully

2

as possible, it will during casting become overheated in relation to the surrounding mold, and as it cannot expand freely, be exposed to shrinkage stresses which will sooner or later give rise to a gap between the sleeve and the mold. The metal will penetrate into this gap during casting.

If such sleeves are not employed as protection for the mold, the casting end of the mold is generally closed with a ring which limits the length of the cast body. Even when using such a ring it is very difficult in practice to prevent the formation of a gap between the ring and the mold into which molten metal can penetrate during casting, with the result that fins will be formed on the cast body so that the mold will be scratched on extraction.

The main object of the present invention is to eliminate these drawbacks and to increase the life of the mold by lengthening the same with an extension, made in one piece or integrally with the mold without any joints with any spaces between the extension and the mold proper into which metal can penetrate during casting.

A further object of the invention is to provide a simple and effective method of manufacturing such a mold by lengthening the mold proper, in conjunction with its manufacture, with an extension located outside the mold and made in one piece with the mold proper without joints with any spaces between them.

One embodiment of a mold according to the invention is shown in the accompanying drawing, in which

Fig. 1 is a longitudinal section of the mold, and
Fig. 2 is a sectional perspective view of the same mold.

In the drawing, 1 indicates the mold which gives the tubular body its outer shape, 2 is the extension at one end of the mold and 3 indicates a socket or other type of stop at the other end of the mold. The difference between the internal diameters, A of the mold, and B at the inner end of the extension, should be at least equal to double the wall-thickness of the cast tubular body. The outer diameter of the extension 2 is suitably made as large as the external diameter of the mold, so that the extension is kept hot, thereby preventing too much of the molten metal remaining there. The extension can, however, be given a smaller external diameter if for example it is desired to make the whole mold as light as possible.

The internal diameter C of the outer end of the extension should not be larger than the internal diameter B of its inner end as the metal will otherwise tend to spray out during casting. Diameter C should preferably be smaller than diameter B in order to facilitate the running of the iron into the mold. The inner surface of the extension 2 will be scored during use and this can give rise to difficulties. It is therefore advisable in manufacturing a new mold to make the taper, that is to say, the difference between diameters B and C, larger than necessary for the inflow of the iron. When the inner surface has become too scored this can be removed by turning, still leaving sufficient taper for the inflow of the iron.

The extension 2 should be at least long enough for the metal to strike the inner surface of the extension and not the inner surface of the mold proper during casting. It has, however, been found advisable and of great importance for the life of the mold to make the extension longer from the beginning. The reason for this is that the gradual development of serious heat cracks in the inner surface of the mold socket 3 can hardly be avoided so that the mold can no longer be used without these cracks being removed by machining. This can only be effected by moving the socket or hub profile further into the mold, thus making the cast body shorter than before, which is usually undesirable. Thus, it is obviously

of value to be able to increase the inner length of the mold proper in the direction of the casting end by short-

causing the extension so that the actual bore of the mold proper will have the same length internally as it had before the cracks in the hub were removed. The extension will then be shorter and should therefore from the beginning be made longer than necessary according to the above.

If for some reason it is not desired or possible to make the extension as long as is appropriate, or if, according to what has been said above, it has been shortened so much that the metal would strike the inner surface of the mold proper during casting, a further extension can be fitted to the extension 2 at its outer end. The fact that there will possibly be a space in the joint between the two extensions is of little significance. The important point is that there must be no space in the joint between the extension and the mold proper.

What I claim is:

1. In the method of manufacturing a hot permanent mold used for centrifugal casting of tubular metallic bodies and for restoring said mold after it has become damaged by use, those steps which comprise lengthening the mold proper, in conjunction with its manufacture, by forming an integral extension thereon with an internal pouring surface at the inlet end of the mold, and, after the end of the mold opposite to said extension has been shortened by machining necessitated by damages caused during the use of the mold, effectively shortening the length of said extension by machining out a portion thereof adjoining said mold to give said portion the same inner diameter as the inner diameter of the mold proper.

2. A hot permanent mold for the centrifugal casting of tubular metallic bodies which comprises, a mold portion and an entrant extension portion, said mold portion being formed as an elongated tubular member with an internal bore extending therethrough, said extension portion being formed for the introduction of molten metal into said bore of said mold portion, said extension portion being formed integrally with said mold portion and

having a conical bore therethrough co-axial with respect to said bore of said mold portion, said conical bore forming an integral continuation of said bore of said mold portion, said conical bore converging in a direction away from said bore of said mold portion and having its greatest diameter less than the diameter of said bore of said mold portion.

3. Arrangement for increasing the life of a hot permanent mold used for centrifugal casting of tubular metallic bodies comprising, extension means for lengthening the mold at the end where the metal is poured in so that said metal will strike the inside of said extension but not the inside of the mold proper, said extension being formed with a conical internal surface having the smallest diameter thereof located at its outer end, the greatest internal diameter of said extension being less than the internal diameter of said mold proper, wherein at least the inner part of said extension is made in one piece with said mold, said internal surface of said extension continuing integrally from the interior surface of said mold proper with a view to preventing the cast metal from penetrating between said extension and said mold proper.

4. Arrangement according to claim 3 wherein the taper of said internal surface of said extension in a newly manufactured mold is greater than necessary for effective introduction of metal into the mold proper whereby a working margin is provided for removing scoring from said internal surface while retaining an internal surface effectively tapered.
